UNITED STATES PATENT OFFICE.

HENRY ROSIER, OF LOWELL, MASSACHUSETTS.

FOLDING REVOLVER.

Application filed April 19, 1922. Serial No. 555,610.

To all whom it may concern:

Be it known that I, HENRY ROSIER, a subject of the King of Belgium, resident of Lowell, in the county of Middlesex and 5 State of Massachusetts, have made a certain new and useful Invention in Folding Revolvers; and I declare the following to be a full, clear, and exact description of the same, such as will enable others skilled in the art 10 to which it appertains to make and use the invention, reference being had to the accompanying drawings, and to letters or figures of reference marked thereon, which form a part of this specification.

15 Figure 1 is a central longitudinal section of the invention.

Figure 2 is a similar view showing trigger pulled to fire, the firing pin being on the point of release.

20 Figure 3 is a side view of the invention with parts folded, parts being in section.

The invention has relation to a folding revolver, having for an object to provide a folding grip or handle and a folding trigger, which when in folded position will render the revolver much more compact, so 25 that it may be more readily placed in the pocket or other place of limited capacity, and which further when folded is made 30 more safe in that it may not be accidentally discharged.

The invention consists in the novel construction and combinations of parts, as hereinafter set forth.

35 In the accompanying drawings illustrating the invention, the numeral 1, designates a revolver frame; 2, the cylinder; 3, the barrel; 4, the center pin upon which the cylinder revolves; 5, the trigger; 6, the 40 pivot of trigger; 7 the pawl pivoted to the trigger at 8 and engaging the ratchet teeth 9 of the cylinder to revolve the latter one step each time the trigger is pulled; 10 is the firing piece pivoted at 12 and having an 45 operating spring 13 and a firing pin 14, the latter pivoted to the firing piece at 15.

The trigger comprises a lever 6^b, fulcrumed at 6 to the frame and having a forward extension 5 pivoted at 6^a thereto and 50 depending therefrom. The trigger lever 6^b is substantially horizontal and underlies the cylinder and its forward extension 5 is foldable upwardly to position approximately parallel with the barrel as shown in Figure 55 2, the joint of said extension and said lever being adapted to prevent any operation of

the lever when said extension is folded as stated. The trigger lever 6^b in firing has a downward operative movement to position shown in Figure 3.

60 The grip or handle of the revolver is shown at 16 and is pivoted to the frame 1 at point 17, being of skeleton form having a back 18 and lateral branches 19 spaced apart by a distance sufficient to enable them in the folded position of the grip as in Figure 2 to embrace the frame 1 and the cylinder at the lower portion thereof. For this purpose the grip is open forwardly, the pivot pin 17 connecting the branches 19 and 70 the back 18 connecting said branches.

65 In the folded position of the grip it underlies the trigger lever 6^b and the joint 6^a, the grip in this folded position being adapted to prevent the downward operative 75 movement of said trigger lever.

70 In the normal or unfolded position of the grip, the same is engaged at the upper end thereof by the tail arm of a lever 21, the latter pivoted to the frame 1 at 22 and 80 acting to hold the grip in normal position. The engagement of lever and grip is effected by means of a tooth 23 of said tail arm fitting in a recess 24 of the upper end of the grip. Operation of the lever 21 by pressing one finger of the operator's hand upon the roughened operating end 25 of the said lever will raise the tail arm of the lever to 85 release the grip, which may then be folded as stated.

90 In the folding of the grip a spring 26 thereof frictionally engages a cam portion 27 of the frame 1 to somewhat impede the folding, and at the end of the folding movement the curved or bent free end of the said 95 spring snaps into a recess 26 at the end of the said cam 27 to hold the grip releasably in folded position.

99 In unfolding the grip, the spring end 100 will ride out of the said recess 26, the unfolding of the trigger will be somewhat impeded by engagement of the spring end with the cam 27, and at the end portion of the unfolding movement the spring end will 105 engage a straight or substantially straight portion 29 of the cam 27 of less eccentricity than the part 27 of the cam, whereby the unfolding movement is rendered more easy, and at the end of the unfolding movement the catch lever 21 engages the grip to maintain it in unfolded position. At the end of the unfolding movement of the grip, the 110

approximately pointed or reduced upper end 30 thereof engages a shoulder 31 of the frame 1 and fits in a recess of said frame to engage the lateral walls of the recess, whereby any lateral movement of the unfolded grip is prevented and the same is held rigidly in unfolded position.

The catch lever is held in engaged position with the grip by a spring 32 engaging under its head end.

I claim: —

In a revolver, a cylinder, a substantially horizontal trigger lever underlying the cylinder and adapted to have a downward operative movement, said lever having a forward extension pivoted thereto and depend-

ing therefrom, in combination with a grip foldable to underlie said cylinder and trigger lever and adapted to prevent said downward operative movement, the frame of the revolver having a cam, and said grip having a spring engaging said cam and adapted to resist unfolding of the grip, the grip having a recess, and a catch lever fulcrumed to the frame and adapted to engage said recess to hold the grip in unfolded position.

In testimony whereof I affix my signature in presence of two witnesses.

HENRY ROSIER.

Witnesses:

ISAIE BARSALOU,
CHARLES THIELS.
